UNITED STATES PATENT OFFICE.

GEORGE J. HELENEK, OF NEW YORK, N. Y.

DISPLAY STAND.

Application filed July 3, 1922. Serial No. 572,494.

To all whom it may concern:

Be it known that I, GEORGE J. HELENEK, a citizen of the United States, and a resident of the city of New York, Long Island City, 5 borough of Queens, in the county of Queens and State of New York, have invented a new and Improved Display Stand, of which the following is a full, clear, and exact description.

10 This invention relates to display stands and has for an object to provide an improved construction which will positively display the articles desired while holding them in a compact arrangement.

15 Another object is to provide a display stand for displaying tubular articles or rolls without utilizing too much floor space in a store.

A still further object is to provide a display stand and holding rack for articles in rolls whereby they may be readily removed and re-inserted without injury and in a minimum amount of time.

In the accompanying drawings—

25 Figure 1 is a side view of a display rack disclosing an embodiment of the invention, a number of rolls being shown in position thereon.

Figure 2 is a top plan view of approximately half of the stand shown in Figure 1.

Figure 3 is a sectional view through Figure 2 approximately on line 3—3.

Figure 4 is a sectional view through Figure 1 approximately on line 4—4, the same 35 being on an enlarged scale.

Figure 5 is a sectional view through Figure 4 approximately on line 5—5.

Figure 6 is a detail perspective view of a locking fixture disclosing certain features of 40 the invention.

Referring to the accompanying drawings by numeral, 11 indicates a base which is preferably made from a number of tubes 12 threaded into a central fitting 13 and bent 45 for producing the upright sections or legs 14 which receive any desired kind of casters 15.

Preferably, the base 11 is larger than the supporting platform 16. This supporting platform, as shown in Figures 4 and 5, 50 is constructed with a sheet metal covering 17 bent at the outer edge for forming a depending flange 18 and resting on suitable supporting arms 19, said arms preferably having bracing ribs to produce the desired 55 stiff structure. Also preferably the covering 17 is riveted or otherwise rigidly se-

cured in place by suitable members 20. The arms 19 may be made from cast metal and when they are formed a central disk 21 is provided which is formed with a tubular section 22 having an inturned annular flange 23 designed to support the tube 24. The flange 23 rests on a suitable bearing washer 25 which in turn rests on the fitting 13 so that the device may be easily rotated. 60

If desired, anti-friction rollers or other anti-friction means may be substituted for the washer 25 which really acts as an anti-friction member. A central or fixed tube 26 is threaded into the fitting 13 and acts as a 70

standard around which the tube 24 moves, said tube loosely fitting over the standard 26. The sleeve 22 is rigidly secured to the tube 24 by any suitable means, as for instance, set screws 27 so that the platform 75 16 and the tube 24 will rotate together. At the upper end of the tube 24 the upper platform 28 is secured rigidly to the tube 24 by the set screws 29 extending through the tubular section 30 of the central disk 31 80

from which the various supporting arms 32 radiate, said supporting arms being preferably formed of stiffening ribs. The covering plate 17 on the base 16 is provided with 85 a number of apertures 33 in which supporting pans 34 are mounted, said pans having upper turned over flanges 35 and pressed out beads 36, the beads 36 engaging the lower surface of the cover 17 while the flanges 35 engage the upper surface and 90 thereby hold the respective pans 34 rigidly in place. These pans are made of the proper size for receiving the lower ends of the various articles 37, said articles being any suitable rolled or tubular article, as for instance, oilcloth. The upper platform 28, 95 similar to the lower platform, is provided with a covering 38 of sheet metal which is formed with a cut-out notch 39 for each of the pans 34, said notches being in line with the pans so that the articles 37 may stand 100 vertically.

Riveted or otherwise rigidly secured to the covering plate 38 and to the respective arms 32 are L-shaped tongues 40 which merge into the respective locking fixtures 41, said locking fixtures being riveted at one end to a catch or bolt 42 and at the opposite end provided with a notch 43 for receiving the bent end 44 of the next catch or bolt 42. The 110 bolt or catch 42 is designed to be easily swung to a position out of the way when

it is desired to move one of the articles 37 out of any of the notches 39. In order that the top platform 32 may be prevented any upward movement, a tubular member 45 is threaded onto the upper end of tube 24 and acts as a clamping nut, said tubular member 45 being preferably provided with a suitable ornamentation 46 at the upper end.

In operation, when the stand is arranged as shown in Figure 1 and it is desired to remove any of the rolls or articles 37 for inspection, the bent end 44 of the desired catch 42 is grasped and the catch raised until the articles 37 may be readily swung out through the opening. The article may then be lifted out of the cup 34 in which it is resting. The article may be replaced by a reverse action. The stand has been designed particularly for oilcloth and as a large number of varieties of this article of commerce must be kept in stock, heretofore much space in the store has been used to produce a proper display. By providing a stand as shown in Figure 1 a larger number of different patterns may be readily disclosed and a minimum amount of space used. In addition, only the particular rolls of oilcloth used will be handled and, consequently, there will be less shop worn sections of oilcloth than were the oilcloth arranged on a supporting platform or counter.

What I claim is:—

1. A display stand of the character de-

scribed, comprising a supporting structure, a pair of spaced platforms for receiving and holding articles to be displayed, the upper platform being formed with notches for receiving part of the article while the lower platform is provided a plurality of cups for receiving the lower ends of said articles, a covering of sheet metal having openings for receiving said cups, a plurality of supporting arms for supporting said covering, said supporting arms merging into a central disk, said central disk having a tubular section formed with its axis arranged at right angles to the plane of the arms, said tubular section having an inwardly extending flange resting on said support, and a standard extending from said support through said tubular structure.

2. A stand for receiving rolled oil cloth or the like comprising a bottom platform having a plurality of openings therein arranged circumferentially adjacent its outer edge, a cup presenting an annular bead and an annular flange above the bead held in each of said openings, the wall of said openings being interposed between the flanges and the beads of the cup, an upper platform having a notch therein in line with each cup in the lower platform, said notches permitting said rolls to be inserted laterally, and a pivotally mounted latch for each notch for locking the rolls therein.

GEORGE J. HELENEK.
